BLEACHING, WASHING, CLEANSING, AND
RINSING AGENTSOtto Lind, Dusseldorf, Germany, assignor to
Henkel & Cie. G. m. b. H., Dusseldorf-Holt-
hausen, Germany, a corporation of GermanyNo Drawing. Application August 14, 1935, Serial
No. 36,117. In Germany August 22, 1934

15 Claims. (Cl. 87—5)

This invention relates to compositions suitable as bleaching, washing, cleansing and rinsing agents, particularly for the treatment of textiles and other fibrous materials, and also, to processes of employing the same.

An object of the invention is to provide compositions possessing outstanding technical advantages including the power of removing yellow discoloration from textiles and also of preventing yellow discoloration due to the use of iron-containing water in the cleaning or other treatment of fibrous materials.

Another object is to provide compositions for the household and for industrial use which besides accomplishing a bleaching action upon fabrics treated therewith also simultaneously effect a thorough cleansing action.

In accordance with the preferred embodiment of the invention, the above objects are accomplished through the provision of compositions which contain in combination essentially one part of an oxygen-yielding compound, one to three parts of a water soluble salt of a phosphoric acid poorer in molecularly combined water than ortho-phosphoric acid and one to three parts of an inorganic salt adapted to react alkaline when in aqueous solution, all parts being by weight. Detailed tests have shown that such compositions can be very advantageously used in the bleaching, washing, cleansing and rinsing of fibrous materials.

Where it is desired to provide compositions which contain also strong detergent powers, there is added to the above composition a suitable quantity of a foaming agent, preferably from two to six parts by weight. The products produced in this manner possess additional advantages, for example, they do not deposit or precipitate out in iron-containing water.

The oxygen-yielding compounds suitable for use in the compositions of the present invention include primarily the per compounds, the per oxides as well as the per salts. There may be used, for example, sodium peroxide and the following per salts: perborates, percarbonates, persulfates, perphosphates and perpyrophosphates. The alkali metal salts, for example, the sodium salts of these compounds are preferred but other readily soluble salts may also be used. In special instances, or for particular uses, it is sometimes more advantageous to use together with the oxygen-yielding compound a suitable amount of a stabilization agent such as, for example, water glass or various magnesium compounds, this ad-

dition being considered within the comprehension of the present invention.

The salts of phosphoric acids which contain less molecularly combined water than orthophosphoric acid, suitable in the practice of the invention include in general the water soluble salts of pyrophosphoric acid, metaphosphoric acid and polyphosphoric acids. The alkali metal pyrophosphates, for example, tetrasodium pyrophosphate, and especially the neutral pyrophosphates produce excellent compositions. The alkali metal metaphosphates may also be used, and as well those which exist in the polymeric form, for example, hexameric sodium metaphosphate. Also, the water soluble polyphosphates are suitable, the alkali metal phosphates being particularly desirable, such as $\text{Na}_5\text{P}_3\text{O}_{10}$ and $\text{Na}_4\text{P}_4\text{O}_{13}$, for example. The alkali metal subphosphates, for example, sodium subphosphate, may also be employed. Although the alkali metal salts of these phosphoric acids are preferred, other salts may be used with considerable advantage, for example, the ammonium salts, and the salts obtained by the use of organic bases, as triethanolamine, cyclohexylamine, aminopropandiols and the like. In certain instances it has been found that mixtures of the above mentioned salts may be employed with better results.

Alkaline reacting inorganic salts in general are suitable in the compositions of the present invention, but the alkali metal carbonates such as soda, the alkali metal phosphates like trisodium phosphate, the alkali metal silicates like sodium metasilicate and the alkali metal borates like borax, are preferred.

The invention comprehends the use of foaming agents of the most varied character and includes as one embodiment, the use of soap, and as a second important embodiment certain soap-like compounds. Where soap is used, commercial grades in general are suitable. As soap-like materials there are used with excellent results the alkali metal or other soluble salts of sulfonated higher molecular fatty alcohols and in particular the sodium salts of the sulfuric acid esters of the aliphatic alcohols or hydrocarbons having more than 8 carbon atoms, preferably from 12 to 22 carbon atoms, such alcohols being producible from natural oils and waxes or from suitable mineral oil fractions by oxidation or other suitable treatment. The alkali metal salts of sulfonated oils may also be used with advantage. In fact all those capillary active compounds in general may be used which possess a high molecular radical on the one hand and a radical im-

parting water solubility on the other hand, for example, the sodium salt of oleyl methyl taurine. The bleaching, washing, cleansing and rinsing agents of the present invention above described 5 may be supplemented by the addition of any one or more of a number of other substances which are generally or sometimes used in rinsing, washing and cleansing agents. For example, an additional wetting agent may be added such as is 10 exemplified by the sodium salt of isopropyl naphthalene sulfonic acid. As a softening or soaking agent, there may be added an enzyme of the nature of pancreatin. Furthermore, agents 15 may be added which increase the penetrating, emulsifying and dispersing power of the composition. The properties may be improved in some cases by the addition of hydrocarbons of the nature of benzene or of its derivatives like the halogenated hydrocarbons, for example, tri- 20 chlorethylene and carbon tetrachloride. In certain cases, the addition of alcohols may be used with advantage. Furthermore, there may be incorporated in the compositions a suitable quantity of a superfatting agent, for example, wool 25 fat, or a polishing and scouring agent, for example, sand or other abrasive.

The method by which the compositions of the present invention are compounded does not constitute any part of the present invention for in 30 general all methods known for the production of washing agents on an industrial scale are suitable. The compositions may be prepared according to known methods in agitating or stirring apparatus of common construction, in ball mills 35 and in other equivalent apparatus. The various ingredients may be brought together in any suitable order. For example, when a product containing soap is to be formed, the alkali pyrophosphate or other equivalent salt is mixed with the 40 soap to form a paste after which the mixture is ground and mixed with the proper proportions of sodium perborate and soda or other equivalent compounds. When compositions free of soap are to be produced, the sodium pyrophosphate or 45 other salt may be initially mixed with the desired quantities of sodium perborate and soda or equivalent materials. A satisfactory mixture can also be obtained by grinding all of the materials together in a dry condition to form a powder. The 50 compositions can be manufactured ready for use or can be mixed wholly or in part at the place of use. Where liquids are to be included in the composition, the various solid ingredients may be separately or simultaneously dissolved in a single 55 body of liquid, or separate solutions of the compounds may be formed and then mixed together.

The novel bleaching, washing, cleansing and rinsing agents of the present invention may be marketed in solid form, for example, as a powder, 60 in flakes, in granules or in strip form. Furthermore, the compositions may be manufactured in liquid form by dissolving the same in liquids, or they may be prepared in dough form or in paste or cream form.

65 Excellent washing, bleaching and cleansing agents may be formed by incorporating together, by anyone of the methods hereinbefore described, the following substances, all parts being by weight:

	Parts
60% soap	50
Tetrasodium pyrophosphate	24
Sodium perborate	8
75 Calcined soda	8

Example 2

	Parts
60% soap	60
Tetrasodium pyrophosphate	11
Sodium perborate	9
Trisodium phosphate	8
Sodium metasilicate	12

Example 3

	Parts
Mixture of the sodium salts of the acid sul-	
furic acid esters of the fatty alcohols	40
Tetrasodium pyrophosphate	20
Borax	30
Sodium perborate	10

Example 4

	Parts
60% soap	50
Sodium polyphosphate of the formula	
$\text{Na}_4\text{P}_4\text{O}_{13}$	20
Calcined soda	20
Sodium perborate	10

Example 5

	Parts
Mixture of the sodium salts of the acid sul-	
furic acid esters of the glycerine ethers	
of the fatty alcohols	30
Tetrasodium pyrophosphate	15
Sodium hexametaphosphate	15
Sodium bicarbonate	30
Sodium perborate	10

Example 6

	Parts
Sodium salt of the oleyl methyl taurine	30
Tetrasodium pyrophosphate	20
Sodium hexametaphosphate	10
Sodium metasilicate	30
Sodium perpyrophosphate	10

The following products are used with particular advantage in the rinsing of fabrics or textiles treated in laundries, all parts being by weight:

	Parts
Tetrasodium pyrophosphate	50
Sodium perborate	17
Calcined soda	34

Example 8

	Parts
Tetrasodium pyrophosphate	27
Sodium perborate	23
Trisodium phosphate	20
Sodium metasilicate	30

Example 9

	Parts
Sodium perborate	20
Sodium polyphosphate of the formula	
$\text{Na}_4\text{P}_4\text{O}_{13}$	40
Calcined soda	40

Example 10

	Parts
Sodium perborate	25
Tetrasodium pyrophosphate	50
Trisodium phosphate	25

Example 11

	Parts
Sodium perpyrophosphate	25
Sodium polyphosphate of the formula	
$\text{Na}_4\text{P}_4\text{O}_{13}$	25
Sodium metasilicate	50

99

3,152,520

3

Example 12

	Parts
Sodium perborate	20
Sodium hexametaphosphate	20
5 Sodium metasilicate	20
Calcined soda	40

Bleaching, washing, cleansing and rinsing agents prepared in accordance with the above 10 examples excel to a considerable degree and in many respects mixtures heretofore known and proposed for the above mentioned purposes. The present compositions may be used with advantage in the household as well as in places like laundries, hospitals and the like for the washing 15 and cleaning of dresses, underwear and other textiles.

The present compositions may be used with 20 special advantage where only iron-containing water is available, for in such case the absorption 25 of iron by the fiber is prevented. Furthermore, the yellow discoloration generally so common and caused by the presence of iron compounds may be removed by the compositions of the present invention. The compositions are also suitable 30 for other fibrous materials and other articles encountered in domestic life and in industrial pursuits.

Whereas the advantages of the compositions of 35 the present invention are generally obtained to the most effective degree when the proportions are as hereinbefore disclosed, it should be understood that many of the advantages may be obtained through the use of compositions of different proportions. For example, the proportion of 40 an alkaline reacting inorganic salt may be increased or decreased to suit any particular purpose requiring particular alkalinity for most effective results. It should be understood further that the invention is to be given a broad interpretation commensurate in scope with that of the terms employed in the claims appended hereto. Furthermore, the claims should be interpreted as including the equivalents of the substances 45 specified therein.

I claim:

1. In compositions for bleaching, washing, 50 cleansing and rinsing, the combination of substances consisting of one part of an oxygen-yielding compound, one to three parts of a water soluble salt of a phosphoric acid containing less molecularly combined water than orthophosphoric acid, and of from 1 to 3 parts of an alkaline metal salt adapted to form an aqueous alkaline solution, said parts being by weight, said phos-

phoric acid salt being present in a proportion constituting not less than 20% by weight of the said mixture.

2. In compositions for bleaching, washing, 5 cleansing and rinsing, the combination of substances consisting of one part of an oxygen-yielding compound, one to three parts of a water soluble salt of a phosphoric acid poorer in molecularly combined water than orthophosphoric acid, one to three parts of an alkaline metal salt 10 adapted to form an aqueous alkaline solution and two to six parts of a saponaceous foaming agent, said parts being by weight, said phosphoric acid being present in a proportion constituting not less than 10% by weight of the said mixture. 15

3. The combination of substances described in claim 1 wherein the oxygen-yielding compound is sodium perborate.

4. The combination of substances described in claim 1 wherein the water soluble salt of phosphoric acid is of pyrophosphoric acid. 20

5. The combination of substances described in claim 1 wherein the water soluble salt of phosphoric acid is tetrasodium pyrophosphate.

6. The combination of substances described in claim 1 wherein the water soluble salt of phosphoric acid is of metaphosphoric acid. 25

7. The combination of substances described in claim 1 wherein the water soluble salt of phosphoric acid is sodium hexametaphosphate. 30

8. The combination of substances described in claim 1 wherein the water soluble salt of phosphoric acid is of a polyphosphoric acid.

9. The composition of matter described in claim 1 wherein the inorganic salt adapted to 35 form an alkaline aqueous solution is soda.

10. The combination of substances described in claim 2 wherein the foaming agent is soap.

11. The combination of substances described in claim 2 wherein the water soluble salt of phosphoric acid is of pyrophosphoric acid. 40

12. The combination of substances described in claim 2 wherein the water soluble salt of phosphoric acid is of metaphosphoric acid.

13. The combination of substances described in claim 2 wherein the water soluble salt of phosphoric acid is of a polyphosphoric acid. 45

14. The combination of substances described in claim 2 wherein the inorganic salt adapted to form an alkaline aqueous solution comprises soda. 50

15. The combination of substances described in claim 2 wherein the alkaline reacting inorganic salt is soda and the foaming agent is soap.

OTTO LIND.
